UNITED STATES PATENT OFFICE.

FRANK. CHASE, OF BOSTON, MASSACHUSETTS.

BOOT AND SHOE FASTENING.

SPECIFICATION forming part of Letters Patent No. 293,145, dated February 5, 1884.

Application filed September 17, 1883. (No model.)

To all whom it may concern:

Be it known that I, FRANK. CHASE, of Boston, in the county of Suffolk and State of Massachusetts, have invented certain new and useful Improvements in Boot and Shoe Fastenings, of which the following is a specification.

The object of my invention is to provide a cheap, simple, convenient, and expeditious fastening for lasting boots and shoes, or connecting the "upper" with the "inner sole," preparatory to receiving the sole proper, secured thereon in any suitable manner; and it consists in the construction of the fastening by means of holes cut through the turned-under edges of the upper and the inner sole, leaving a "core" and passing a cord or thread over such holes; then driving the cores back into the holes from which they were cut; carrying the cord or thread down into the holes beneath the ends of the cores, and leaving it connected or continuous between the holes from which it extends at each side of the core, in the line of the series of fastenings, as hereinafter more fully described, and set forth in the claim.

Figure 1 represents a plan of the bottom of a shoe having the upper and the inner sole secured or connected together or "lasted" in the manner embracing my invention. Fig. 2 represents a vertical section through the inner sole and upper, showing my invention.

A represents the inner sole, applied and secured upon the bottom of a last as usual; and B shows the turned-under edges of the upper, as heretofore, the said upper being secured in position upon the inner sole by punching holes through the upper and through the inner sole, by means of a hollow punch, so as to remove

from said upper and sole a core, E, which is retained within the said punch, and a cord or thread, L, passed over said hole; and then said core E is forced or driven from the punch downward upon the said cord or thread, (drawn over such hole,) and within said hole beneath the bottom of said core E, as it is driven back into the hole from which it was removed by the hollow punch, thus repeating the said operation, forming a series of holes and fastenings at short intervals around near the edges of the sole throughout the same to the point of beginning, leaving the said thread or cord E drawn down snugly upon the surface of the said turned-under portion of the said upper B, between the holes, so as to hold the same securely and evenly upon the inner sole at all points, as shown in Fig. 1. It will be seen and understood that the said cord or thread is carried by the core down into the hole at each point of connection, and that said thread or cord continues or extends from hole to hole around all portions of the said sole.

Having thus described my invention, what I claim is—

That improvement in uniting the uppers and soles of boots and shoes consisting in forming holes in the parts to be united, by punching out or removing portions of the same, then passing a cord or thread over such holes, then forcing the removed portions or cores back into the holes, carrying with them the overlaid cord or thread, thus forming a continuous line of fastening, substantially as set forth.

FRANK. CHASE.
